UNITED STATES PATENT OFFICE.

GEORGE A. JOHNSON, OF CHICAGO, ILLINOIS, ASSIGNOR TO W. H. MINER, INC., OF CHICAGO, ILLINOIS, A CORPORATION OF DELAWARE.

FRICITION SHOCK-ABSORBING MEANS.

Application filed May 29, 1925. Serial No. 33,596.

This invention relates to improvements in shock absorbing means.

One object of the invention is to provide a friction shock absorbing means especially adapted for railway draft riggings, adapted to cushion extremely heavy shocks and having great column strength.

Another object of the invention is to provide a friction shock absorbing means whereby in the main followers abut upon full compression of the mechanism to provide an overload column of great strength independent of the shock absorbing mechanism and thereby relieve the friction shock absorbing mechanism proper and especially the friction shell from undue strain.

Other objects and advantages of the invention will more fully and clearly appear from the description and claims hereinafter following.

In the drawing forming a part of this specification, Figure 1 is a longitudinal, sectional view of a portion of a railway draft rigging, showing my improvements in connection therewith, the section through the shell and friction elements therewithin corresponding to two section planes at approximately 120° apart. Figure 2 is a transverse, vertical, sectional view corresponding substantially to the line 2—2 of Figure 1. And Figure 3 is a horizontal sectional view of a portion of a railway draft rigging, illustrating a different embodiment of the invention, the section being taken on two different planes. Referring first to the embodiment of the invention illustrated in Figures 1 and 2, 10—10 indicate channel-shaped center or draft sills of a railway car underframe, to the inner sides of which are secured front stop lugs 11—11 and rear stop lugs 12—12. The inner end portion of the drawbar is indicated at 13 and has operatively associated therewith a yoke 14 of well-known form, the yoke being provided with a pocket 45 adapted to receive the inner end of the drawbar and the drawbar being attached to the yoke by a transverse key 15 operating in slots 16 in the side walls of the yoke and slots 17 in the draft sills. The entire shock 50 absorbing means, as well as the rear main follower 18 are operatively disposed within the yoke, and the yoke in turn supported in operative position by a detachable saddle plate 19 fixed to the draft sills.

The improved shock absorbing means, as

shown, comprises broadly a combined follower and overload column A; and a friction shock absorbing mechanism proper, including a combined friction shell and spring cage B, a pressure-transmitting wedge C, 60 three friction-shoes D, D and D, three anti-friction rollers E, E and E, a main spring resistance F, a spring follower disk G, and a retainer bolt H.

The combined front follower and overload column A comprises a substantially rectangular casing having a transverse front end wall 20 co-operating with the stop lugs 11 in the manner of the usual front follower, and relatively heavy spaced side walls or 65 arms 21—21 extending rearwardly. The side walls 21 are cut away, on the inner sides as indicated at 22 to provide curved interior surfaces. The column is open at the top and bottom as indicated at 23 to accommodate 70 the usual enlargements at the top and bottom of the friction shell. The inner ends of the side walls 21 are normally spaced from the rear follower 18 as most clearly shown in Figure 1, the distance between the 75 follower 18 and the inner ends of the arms being equal to the full compression stroke of the mechanism.

The combined friction shell and spring cage B which is in the form of a generally 80 cylindrical casting having the friction shell proper 24 thereof formed at the open or front end is telescoped within the column element of the front follower. Rearwardly 85 of the friction shell proper, the casting provides a cylindrical spring cage or casing 25, and at its rear end the casing has an integral transverse wall 26 bearing on the follower 18. On the interior, the shell 24 is provided with a true cylindrical friction surface 27.

The wedge C through which the pressure is transmitted is in the form of a cylindrical block having a transverse front bearing face 28 adapted to co-operate with the inner surface of the transverse end wall 20 of the front follower. At the inner end, the wedge C is provided with three inwardly and rearwardly converging flat faces 29 symmetrically arranged around the center or the axis 90 of the wedge. At the inner end of each wedge face 29, a shoulder 30 is provided 95 adapted to form a seat for the corresponding anti-friction roller E.

The friction shoes D are all of like con-

struction, each having an outer friction surface 127 adapted to co-operate with the corresponding friction surface 27 of the friction shell. Each of the shoes has a lateral 5 enlargement on the inner side thereof having a face 129 correspondingly inclined to and adapted to co-operate with one of the faces 29 of the wedge. The enlargement of each shoe is provided with a shoulder 31 forming 10 a seat for the corresponding anti-friction roller E. As most clearly shown in Figure 1, the three anti-friction rollers are interposed respectively between the three wedge faces 15 of the main wedge C and the three friction shoes.

The main spring resistance F comprises a relatively heavy outer coil 32 and a light inner coil 33, the outer coil being interposed between the inner ends of the friction shoes 20 and the transverse end wall 26 of the spring cage. The small coil 33 has its rear end bearing on a hollow boss 34 projecting inwardly from the end wall 26 of the spring cage. The front end of the spring 33 bears directly on the spring follower disk G which is interposed between the spring and the inner ends of the enlargements of the shoes. The retainer bolt H has its opposite ends 25 anchored to the hollow boss 34 and the main wedge respectively and maintains the mechanism of uniform overall length and holds the spring resistance under initial compression.

The operation of my improved means is 30 as follows, assuming a compression stroke: The combined front follower and overload column and rear follower 18 will be moved relatively toward each other, thereby carrying the main wedge and friction shoes 35 inwardly of the friction shell, at the same time spreading the shoes apart and compressing the main spring resistance. This action will continue either until the actuating force is reduced or until the inner ends 40 of the side walls of the overload column engage the rear follower 18, whereupon the pressure will be transmitted directly from one to the other through the column means 45 relieving the friction shell and main spring resistance element from undue strain.

Although, as illustrated in the drawings, the outer end of the friction shell will be engaged substantially simultaneously with the engagement of the column arms with the 50 rear follower, it will be evident that the front end of the friction shell may be so spaced from the inner surface of the transverse end wall 20 of the combined follower and overload column that there will be no 55 actual contact between the wall 20 and the friction shell upon full compression of the mechanism.

Referring next to the embodiment of the invention illustrated in Figure 3, the usual 60 draft sills are indicated by 110—110, to which

are secured front stop lugs 111—111 and rear stop lugs 112—112. The inner end portion of the drawbar is indicated by 113, to which is operatively connected the hooded yoke 114. The shock absorbing means is 70 operatively supported within the yoke. The movable parts of the draft rigging are supported by the usual saddle plate, not shown.

The improved shock absorbing means, as 75 shown in Figure 3, comprises front and rear follower acting members A'—A'; and a shock absorbing mechanism proper including a friction shell B', having the usual spring resistance disposed therein co-operating with friction wedge shoes D'—D', a main wedge C', co-operating with the shoes 80 in the usual manner.

The friction shock absorbing mechanism proper, shown in Figure 3, corresponds in 85 all respects with that hereinbefore described, and shown in Figures 1 and 2.

The front and rear followers A' are of like construction, each comprising a relatively heavy plate-like section 120 of rectangular outline, having a pair of inwardly 90 extending arms 121 at the opposite sides thereof. The main body portions of the followers A' co-operate with the corresponding stop lugs in the manner of the usual main follower. The arms 121 of the two followers 95 are longitudinally disposed and project inwardly toward each other, having their inner ends spaced apart a distance equal to the normal compression of the mechanism. As shown in Figure 3, the inner faces of the 100 arms 121 are cut away thereby providing top and bottom overhanging portions 122 projecting laterally inward therefrom. The overhanging portions 122 at the opposite sides of each follower A' are adapted to embrace the friction shell proper, thereby preventing lateral and vertical displacement of the same. The faces of the cut away portion of the arms 121 are curved and preferably correspond to the exterior contour of 105 the friction shell. The inner end of the friction shell B' is adapted to abut the inner face of the main body section 120 of the rear follower A' and the wedge C' is adapted to abut the inner face of the main body portion 120 of the front follower A'.

The entire mechanism is preferably maintained of overall uniform length by a pair of retainer bolts H'—H', disposed at opposite sides of the friction shell. As shown, one of the bolts H' at the opposite side is arranged at the bottom of the mechanism. The front and rear ends of the bolts are anchored respectively to the main body portions 120 of the corresponding followers A', the arms 121 of the followers being provided with longitudinal bores adapted to accommodate the shanks of the bolts. The head and nut at the opposite ends of each bolt are accommodated in suitable recesses of suffi- 110 115 120 125 130

cient depth to permit full compression of the mechanism.

It will be evident that the retainer bolts may be entirely omitted.

5 The operation of the embodiment of the invention illustrated in Figure 3, is substantially the same as that hereinbefore described. However, it is pointed out that when the friction shock absorbing mechanism is fully compressed, the inner ends of the arms 121 of the front and rear followers A' will be brought into abutment and the load transmitted directly through the followers A' to the stop lugs on the draft sills.

15 From the preceding description, taken in connection with the drawings, it will be evident that I have provided an extremely simple and efficient overload column for transmitting the actuating force from one follower to the other, thereby relieving the friction shell from overload. It will also be evident that by providing the overload column, which is independent of the shock absorbing mechanism proper and especially 25 independent of the friction shell, a much lighter shell may be employed than is now commonly used, it being the general practice at present to limit the relative movement of the followers by direct engagement with 30 the friction shell, the latter serving as an overload column, thus necessitating the use of a very heavy friction shell casting.

While I have herein shown and described what I now consider the preferred manner 25 of carrying out my invention, the same is merely illustrative and I contemplate all changes and modifications that come within the scope of the claims appended hereto.

I claim:

40 1. In a shock absorbing means, the combination with front and rear relatively movable follower elements, said elements having stop column means associated therewith for limiting the relative movement of said elements; of a complete friction shock absorbing mechanism including a friction shell within said column means; friction shoes within the shell; a main wedge and a spring resistance co-operating with said shoes.

50 2. In a draft rigging, including spaced draft sills having stop lugs thereon, the combination with front and rear relatively movable followers, one of said followers having a heavy stop column associated therewith, said stop column having substantially

solid walls and being adapted to co-act with the other follower to limit relative movement of said followers; of an independent friction shock absorbing mechanism spaced from said draft sills, said mechanism being disposed within said column and co-operating with said followers, said column walls occupying substantially the entire available space between the draft sills and said mechanism.

65 3. In a friction shock absorbing means, the combination with front and rear, relatively movable followers; of a stop column casting for limiting relative movement of said followers; a friction shell telescoped with in said casting; friction shoes within the shell; a lateral pressure creating means co-operating with said shoes; and a spring resisting relative movement of said shell and shoes.

70 4. In a friction shock absorbing means, the combination with relatively movable front and rear followers; one of said followers having longitudinally disposed arms having their free ends normally spaced a predetermined distance from the other follower and adapted to engage the latter upon full compression of the mechanism to transmit the actuating force directly from one follower to the other; of an independent friction shock 85 absorbing mechanism including a friction shell embraced by said arms, a friction wedge system co-operating with the shell, and a main spring resistance within the shell co-operating with said friction wedge system.

90 5. In a shock absorbing means for railway draft riggings, including draft sills having stop lugs thereon, the combination with a friction shock absorbing mechanism proper, including follower means, a longitudinally 95 disposed friction member, friction elements cooperating therewith, lateral pressure creating means cooperating with said elements, and a main spring resistance, said shock absorbing mechanism being spaced from the 100 draft sills; of an independent, solid, overload column means embracing said friction shock absorbing mechanism, said column overload means occupying substantially the entire available space between the draft sills and 105 shock absorbing mechanism.

In witness that I claim the foregoing I have hereunto subscribed my name this 27th day of May 1925.

GEORGE A. JOHNSON.
